ADJUSTABLE BRAKE LATCH

Orville N. Whitefield, Sonora, Tex.

Application June 27, 1949, Serial No. 101,605

2 Claims. (Cl. 74—533)

1

This invention relates to an adjustable brake latch especially adapted for use with well drilling spudder machines.

The primary object of this invention is to provide a brake latch which is adjustable to hold the brake lever of a spudder machine in any desired position so that the correct amount of line will be delivered when desired.

A further object of this invention is to provide a brake latch of the character described which will allow fine adjustment of the brake lever by a simple manipulation of the latch.

And yet another object of this invention is to provide an adjustable brake latch of the character described which is relatively simple in design and construction, easy to assemble to the rig of a well drilling machine, easy to manipulate and very efficient for its intended purpose.

A further object of this invention is to provide in a well drilling machine having a line-delivery reel, a brake therefor and a lever for tightening the brake; an adjustable latch for permitting variable adjustment of the brake comprising a bracket having an elongated slot for receiving the lever, spaced notches in said bracket extending into said slot for retaining the lever at a desired adjusted position, means for slidably attaching said bracket to the machine, and means for adjustably raising and lowering said bracket.

These, together with various ancillary objects and features of the invention which will later become apparent as the following description proceeds, are attained by the device, a preferred embodiment of which has been illustrated, by way of example only, in the accompanying drawings, wherein:

Figure 1 is a perspective view of the device shown attached to a well drilling spudder machine;

Figure 2 is a top plan view of the device shown in Figure 1; and

Figure 3 is a sectional view taken substantially in the plane of section line 3—3 of Figure 1.

Specific reference will now be made to the drawings. In the several views, in the accompanying drawings and in the following specification, similar reference characters indicate corresponding elements throughout.

Indicated generally at 10 is the frame of a well drilling spudder machine which is provided with the conventional reel 12 upon which is wound a line 14. Embracing the reel are brake bands 16 which may be tensioned or tightened by a lever

18 of the frame and a wire line 20 which is wound around the reel 12. The frame 10 is provided with a top plate 22 which is secured to the frame by bolts 24. The top plate 22 is provided with a slot 26 for receiving the lever 18. The slot 26 is of inverted, L-shaped construction for receiving the lever 18 and preventing the latter from falling off the bracket 22 when it is positioned in an inoperative or rest position.

The bracket 22 is provided with a plurality of vertically spaced teeth or notches 30 for selectively receiving a lug 32 depending from the lever

18 so that the proper tension on the reel 12 can be applied to the brake bands 16 to allow for the delivery of a certain amount of line 14. As will be readily understood, the tension on the brake bands 16 will be limited by the distance between the teeth 30, and it therefore becomes necessary to provide a means for moving or adjusting the bracket 22 to allow for fractional adjustment between the teeth. The combined means of attaching the bracket to the frame and the means for raising and lowering the attaching means efficiently performs this function as will be seen hereinafter.

Adjacent the top and bottom of the bracket 22 are vertically extending slots 34 (see Figure 3) and extending through the slots are bolts 36 which are threaded at one end for attachment to the frame 10. At their free ends, the bolts 36 are provided with heads 38 having internally threaded vertical bores 40 for receiving an externally threaded elongated screw 42 which is provided at its free ends with heads or closure nuts 44. A pair of L-shaped brackets 46 are secured by means of screws 48 to the latch bracket 22, one leg of each of said brackets being apertured as at 50 to receive the elongated screw 42 and abut the heads 44.

In practical operation, the lever 18 is moved upwardly to engage a selected tooth or notch 30 to apply the proper tension on the reel 12 for the delivery of a certain amount of line 14. If this adjustment is not efficient and the movement of the lever 18 upwardly to the next tooth 32 would apply too much tension to the reel 12, the elongated screw 42 is rotated so that the bracket 22

50 to apply the proper tension on the reel 12 for the delivery of a certain amount of line 14. If this adjustment is not efficient and the movement of the lever 18 upwardly to the next tooth 32 would apply too much tension to the reel 12, the elongated screw 42 is rotated so that the bracket 22

moves upwardly relative to the frame 10 to the desired adjusted position, as will be readily understood.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. In combination with a lever adapted to actuate a brake, an adjustable latch comprising a bracket having an elongated slot for receiving the lever, spaced notches in said bracket extending into said slot for retaining the lever at a desired adjusted position, spaced slots in said bracket and headed screws extending through said slots and adapted to be secured to a support, and means for

adjustably raising and lowering said bracket, said means including threaded bores in the heads of said screws, an elongated threaded bolt engaged in said bores, and means securing said threaded bolt to said bracket.

2. The combination of claim 1 wherein said last-named means includes apertured brackets receiving the ends of said threaded bolts and fastening pins securing said brackets to said first named bracket.

ORVILLE N. WHITEFIELD.
